FIG. 1.

FIG. 2.

FIG. 3

FIG. 4.

JAIME CATEULA
INVENTOR:
By *Ottolment*
his Attorney.

UNITED STATES PATENT OFFICE.

JAIME CATEULA, OF BUENOS AIRES, ARGENTINA.

CUPPING GLASS.

Application filed May 23, 1922. Serial No. 563,126.

To all whom it may concern:

Be it known that I, JAIME CATEULA, a citizen of the Argentine Republic, residing at Calle Maipu 671, Buenos Aires, Argentine Republic, have invented new and useful Improvements in Cupping Glasses, of which the following is a specification.

This invention relates to certain new and useful improvements in cupping glasses which I have devised in connection with the actual type of said device, generally formed of a single piece of glass and which operates by rarefaction of the air contained therein, produced by the combustion of any suitable liquid fuel, with preference alcohol as this product is being kept at all homes and besides is most convenient as regards its combustive and antiseptic properties.

The cupping glass in accordance with this invention proves most convenient in use for the patient as well as for the operator; in fact, the former may remain in the position he likes best without running the risk of being burnt, while the latter who does not require to be expert, is enabled to proceed without precipitation and may operate with entire sureness and efficiency as he knows that no alcohol or other burning fluid is liable to be spilled or run out and burn the patient or set fire to the bed clothes, as is frequently the case when using cupping glasses of the ordinary type.

The invention substantially consists in forming the cupping glass in its interior, at a suitable level, with an annular groove wherein the burning fluid is infallibly caused to accumulate when turning the receptacle, thus preventing the same from spreading over the entire inner surface of the same.

In order to facilitate the understanding of this invention, illustrative drawings have been annexed to this specification, wherein:

Figures 1 and 2 respectively illustrate a side elevation and a cross section of the im-

proved cupping glass in accordance with my invention.

Figures 3 and 4, respectively, are similar views of a modified embodiment of the improved cupping glass.

In said drawings, 1 indicates the body part of the cupping glass, made of any suitable size and formed in its interior with a circular groove 2 which, as indicated in Figures 1-2 and 3-4 of the drawings, may conveniently be arranged at half the height of the receptacle or at a level near the mouth of the same.

Said corrugation or groove has for object the small amount of burning fluid which is spreading over the inner surface of the receptacle as the latter is being turned for applying the mouth thereof to the epidermis of the patient.

It will be readily understood that any excess of the combustive fluid will gather within and be retained by the said groove and by this means said fluid will be prevented from unduly spreading or being spilled and burn the patient or set fire to the bed clothes or the like.

Having now described my said invention and in which manner the same is to be performed, I declare that what I claim and desire to secure by Letters Patent, is:

A cupping device of glass or other suitable material and of any convenient size, provided with an annular groove in the interior thereof, either parallel or otherwise arranged with regard to the mouth thereof, at any suitable level of the same, for the purpose of gathering and retaining the slight excess of burning fluid which spreads over the inner walls of the cup as the latter is being turned into its operative position, all substantially as above described with reference to the accompanying drawings and for the purposes set forth.

JAIME CATEULA.
